Patented Nov. 9, 1965

202,791

COMBINED PLAY HORSE, TABLE AND SEATING UNIT

Arlene P. Smith, 10445 Irma Ave., Tujunga, Calif.

Filed Oct. 27, 1964, Ser. No. 82,339

Term of patent 7 years

(Cl. D33—14)

FIG. 1.

FIG. 2.

FIG. 3.

FIG. 4.

FIG. 5.

FIG. 6.

FIGURE 1 is a perspective view of the device when used as a play horse;

FIGURE 2 is a side view as seen from the opposite side viewed in FIGURE 1;

FIGURE 3 is a front elevational view;

FIGURE 4 is a top view of FIGURE 2;

FIGURE 5 is a rear elevational view, and

FIG. 6 is a perspective view of the combined play horse, table and seating unit with the saddle removed and the article in position for use as a table.

I claim:

The ornamental design for a combined play horse, table and seating unit, substantially as shown.
